UNITED STATES PATENT OFFICE.

WILLIAM H. SHEPPARD, OF SAN FRANCISCO, CALIFORNIA.

GEOLOGICAL-FAULT GUIDE.

1,425,705.

Specification of Letters Patent. Patented Aug. 15, 1922.

Application filed July 9, 1919. Serial No. 309,546.

To all whom it may concern:

Be it known that I, WILLIAM H. SHEPPARD, a citizen of the United States, residing in the city and county of San Francisco, 5 in the State of California, have invented certain new and useful Improvements in Geological-Fault Guides, whereof the following is a specification.

This invention relates to geological-fault 10 guides.

The invention is intended to facilitate the study of geologic and mineral formations, and to indicate, especially to the miner, the probable course of veins and other formations. To this end the invention consists in a series of blocks, which in normal juxtaposition may constitute a rectangle, or other figure. These blocks are separated by planes which may represent cleavage or fault 15 planes, the block in its entirety representing the country rock of a district. On the surface of the block may be marked the strata of the district, preferably as it would appear before displacement, and any veins 20 that may require study.

The combined block thus represents a section of country, and by sliding the sub-members upon each other, will indicate the probable course of the formation to be studied.

To illustrate my invention I have selected the device illustrated in the accompanying two sheets of drawings, the same consisting of a rectangular block divided into five sub-members, by planes as will be set forth hereinafter. The figures of the drawing are as follows:—

Figure 1 is a perspective view of the rectangular compound block, composed of the five sub-members, and having marked thereon the normal strata, and a vein.

Figure 2 is a perspective view of the same after a distortion, in which only one sub-member is shifted.

Figure 3 is the same again, after a greater distortion, in which all the sub-members are shifted.

Figure 4 is a perspective view showing two only of the sub-members, the others being omitted for clearness of view, both of the sub-members shown being displaced, one of them being turned almost at right angles to its normal position.

Figure 5 shows the two larger sub-members butt to butt, the others being omitted.

Figure 6 shows the two larger sub-members in normal position, the others being omitted.

Figure 7 shows the shape of the third and fourth sub-members.

In the drawings:—A is the compound rectangular block, made up of the sub-members 1, 2, 3, 4, 5. The member 1 is a quasi parallelopipedical solid, whose cross-section in one direction is a trapezoid. The member 2 is similar to member 1, but its acute angle is cut off, making it a seven sided solid having two pairs of opposed parallel sides, with one side at right angles to both pairs, and the other two sides forming an obtuse wedge. Members 3 and 4 are both six sided solids with two pairs of parallel faces, and the other two faces converging. The two members, 3 and 4, differ only in size, and, when placed together and in conjunction with members 5, constitute a wedge, of which member 5 is the edge. Member 5, is a five sided solid, of which two sides are parallel and of triangular shape, and the other three sides disposed about the same.

Upon the compound block, thus constituted, may be marked the course of the normal strata, as indicated by the dotted lines *a*, *a*. In practice these strata may be marked by colored streaks or the block may be built of actual layers. The block may also have marked thereon a vein *b*, or a number of veins may be marked thereon. I have marked but one, for the sake of simplicity.

In use, the compound block A being marked as indicated to show the normal strata, and with a vein *b*, which in this case may indicate a surface vein, may rest normally upon a table. The block being tilted, say to the left, will assume the position shown in Figure 3, exhibiting a main fault and local faults, and the displacement of the vein, and the user will see from the device what course he should follow to find his vein, if he loses it because of fault. In the particular instance selected for illustration, member 1 will show the foot-wall of the fault, and member 2 the hanging-wall of the fault, whilst members 3, 4, and 5 show the shears. The open spaces *c*, *d*, *e*, shown in Figure 3 developed by the displacement, would naturally be filled by infiltration or otherwise, and would constitute lenses of ore, whose location would be indicated by

the block, and could be sought for accordingly.

Having thus described my invention, and an embodiment of it, in the full, clear and exact terms required by law, and knowing that it comprises novel, useful and valuable improvements in the art to which it pertains, I here state that I do not wish to be limited to the precise construction and arrangement of the several parts, as herein set forth, as the same may be variously modified by a skilled mechanic without departing from the spirit of the invention.

What I claim and desire to secure by Letters-Patent of the United States, is the following, to wit:

1. A device of the character described, comprising a block adapted to represent fault planes in geological formations, said block being divided into a plurality of oblique-angled sub-members.

2. A device of the character described, comprising a block adapted to represent fault planes in geological formations, said block being divided into a plurality of sections having each a different shape fitted together.

3. A device of the character described, comprising a block adapted to represent fault planes in geological formations, said block being sub-divided into a plurality of

sections of different sizes and angles fitted together.

4. A device of the character described, comprising a block divided into a plurality of oblique-angled sub-members fitted together on plane surfaces and adapted to slide thereon to represent fault planes in geological formations.

5. A device of the character described, comprising a block divided into a plurality of oblique-angled sub-members, said members having marked thereon the normal strata of the country, and such veins and formations as may be desired, whereby the shifting of the members on each other to correspond with the shifted strata of the country represented will indicate the shifted position of the vein or other formation.

6. A device of the character described, comprising a series of oblique-angled sub-members, fitted together on plane surfaces, and adapted to be shifted with reference to each other upon said plane surface.

In testimony that I claim the foregoing I have hereto set my hand this 21st day of June, 1919, in the presence of two witnesses.

WILLIAM H. SHEPPARD.
